UNITED STATES PATENT OFFICE.

JAMES McDONALD, OF LOS ANGELES, CALIFORNIA.

WRENCH.

Application filed June 9, 1926. Serial No. 114,677.

My invention is a wrench of a sliding jaw type in which a screw engaging the rack is utilized to adjust the jaws of the wrench.

An object of my invention is the construction of a hand wrench of a sliding jaw type in which a rack and a rotating screw are utilized to adjust the jaws, the screw being shiftable to be disengageable from the rack to allow quick adjustment.

Another feature of my invention is the mounting of the jaws relatively to each other that they may have a slight rocking motion by providing a yoke on one of the jaws encircling the bar supporting the other jaw, this yoke allowing a slight rocking movement.

Another feature of my invention is in the gripping jaws having one of the jaws slightly movable towards and from the other, this jaw sliding on the yoke.

My invention will be more readily understood from the following description and drawings, in which;

Figure 1 is a part longitudinal section and part elevation of my wrench;

Fig. 2 is a front edge view as if taken in the direction of the arrow 2 of Fig. 1;

Fig. 3 is a side elevation of the wrench;

Fig. 4 is a transverse section of the line 4-4 of Fig. 1;

Fig. 5 is a transverse section on the line 5-5 of Fig. 1.

In the wrench I employ a handle 1 to which is connected a bar 2, the handle and bar may be considered as relatively stationary. Longitudinal shoulders 3 are formed on each side of the bar and inset from such recesses are rack teeth 4. The outer end 5 of the fixed bar is slightly bevelled, the slope being inwardly towards the rack side of the bar. The deep socket 6 extends longitudinally of the bar and a plug 7 fits therein, this plug being attached to a shiftable jaw 8 by means of a screw threaded connection 9 or the equivalent. A spring 10 connected to the plug and to the base of the socket by a pin or the like 11 normally draws the shiftable jaw in close contact with the end face of the bar.

A sliding bar 12 has a jaw 13 on its outer end and is provided with a yoke 14 at its inner end, this yoke encircling the bar 2. Slideways 15 and 16 are formed in the shiftable bar and carry slidable blocks 17 in which are journaled the bearing ends 18 of the screw 19. Springs 20 fitted in the re-

cesses 21 normally bear on the blocks 17 thrusting the screw into engagement with the rack teeth.

A loose yoke 22 encircles the bar 12 and the outer end of the bar 2, there being brackets 23 secured to the bar 2 on each side thereof preventing said yoke from slipping downwardly on the bar towards the yoke 14. This yoke has an inclined bevelled surface 24 of substantially the same slope as the outer end 5 of the bar 2. The jaw 8 is of sufficient width to rest on the surface 24 of the yoke and has arms 25 extending on each side of the bar 12 retaining the shiftable jaw in proper relation to the bar 2 and the bar 12. A spring 26 fitted in a recess 27 transversely of the bar 2 at the outer end normally draws these bars towards each other at the outer portion.

A pair of pins 28 are secured to the opposite sides of the yoke 14 and extend into the longitudinal shoulders 3, these pins preferably having small rollers 29 thereon. Such construction prevents the ends of the rack 4 from engaging the end 30 of the bar 12.

The manner of utilizing my wrench so far as the quick adjustable feature is concerned is substantially as follows:

It will be manifest that the jaws can be shifted relative to each other by rotating the screw 19 in engagement with the rack 4, however, when a quick adjustment is desired it is merely necessary to withdraw the screw from engagement with the rack by compressing the spring 20 and thereby shift the bars 2 and 12 relative to each other, thereby forming a quick adjustment of the jaws.

In regard to the feature of my wrench giving a tight grip on the nut or other article engaged between the jaws, such as a pipe, it will be seen that the bars 2 and 12 may have a slight rocking movement and in such action compress the spring 26. When the bars 2 and 12 are rocked away from each other the jaw 8 is carried away from the bar 12 and in such action through the medium of the plug 7 is slid upwardly on the incline 24 of the yoke 22. Such action therefore separates the shiftable jaw 8 slightly from the end face 5 of the bar 2. This action is shown by the dotted lines in Fig. 1, thereby forcing the two jaws 8 and 13 slightly closer to each other by this rocking movement of the jaws. On the jaws resuming their position as shown in Fig. 1, which motion is caused by the spring 26, the spring 10 with-

draws the jaw 8 until it contacts with the outer end of the jaw 2, thereby slightly separating the two jaws 8 and 13 irrespective of any adjustment by the screw 19.

5 It will thus be seen that with my wrench I have provided for a quick adjustment for regulating the jaws and also for an automatic adjustment of one jaw relative to the other in the action of gripping and turning 10 an article such as a nut, pipe or the like.

It will be manifest that these features may be considerably changed in general construction and in specific details to suit different types of wrench. Such changes 15 however, will be within the spirit of my invention as set forth in the description, drawings and claims.

Having described my invention, what I claim is:

20 1. A wrench comprising in combination a handle having a bar connected thereto with a shiftable jaw on the end of the bar, a slideable bar having a rigid jaw, means to slide said bar relative to the bar attached to the handle, a yoke encircling both bars and allowing slight rocking movement, the shiftable jaw and the yoke having inclined surfaces whereby the swinging apart of the bars forces the shiftable jaw slightly 30 towards the rigid jaw.

2. A wrench comprising in combination a handle having a bar fixed thereto, a slideable bar having a fixed jaw, a yoke encircling said bars, means on the fixed bar to restrain 35 the yoke from longitudinal movement towards the handle, a loosely mounted jaw on the end of the fixed bar, means retaining said jaw normally in engagement with the

yoke, the yoke and the jaw having inclined surfaces, and a spring tensioned to normally 40 force said bars towards each other adjacent their outer ends.

3. A wrench comprising in combination a pair of relatively slideable bars having jaws mounted on their outer ends, one of said 45 bars having a pair of longitudinal shoulders and a rack, the other bar having a yoke fixed thereto and engaging around the other bar, slideways in one of the bars, blocks forming 50 journals slideable therein, a screw mounted in said journals, and springs bearing against said blocks normally pressing the screw into engagement with the rack, and pins in the yoke engaging the shoulders.

4. A wrench as claimed in claim 3, a yoke 55 loosely surrounding the said bars adjacent the outer end of one of the bars, a loosely mounted jaw bearing on said yoke, and means to retain the said jaw in engagement with the yoke, the yoke and the jaw having 60 inclined meeting surfaces.

5. A wrench comprising in combination a pair of relatively slideable bars, a rigid jaw on one and a loosely mounted jaw on the other, a yoke encircling said bars, the loose 65 jaw engaging the yoke, said yoke having an inclined surface to slide the loose jaw on the relative movement of said bars, the loose jaw being mounted on one of the bars, said 70 bar having a deep socket, a plug secured to the jaw, and a spring in the socket secured to the plug.

In testimony whereof I have signed my name to this specification.

JAMES McDONALD.
